UNITED STATES PATENT OFFICE.

GEORGE MARSHALL, OF FREMONT, NEBRASKA.

REINFORCED-CONCRETE CROSS-TIE.

1,172,029.

Specification of Letters Patent. Patented Feb. 15, 1916.

Application filed December 11, 1915. Serial No. 66,293.

To all whom it may concern:

Be it known that I, GEORGE MARSHALL, a citizen of the United States, residing in Fremont, in the county of Dodge and State 5 of Nebraska, have invented certain new and useful Improvements in Reinforced-Concrete Cross-Ties, of which the following is a specification.

This invention relates to railway cross-ties constructed of cement or concrete reinforced by metal rods or similar reinforcing means, and the object of the invention is to provide a cross-tie of this class which can be easily made, laid and repaired and 15 which, while strong and durable, has sufficient elasticity and flexibility to relieve the rails and the road-bed of much of the strain to which they would otherwise be subjected.

20 Further objects of the invention are to provide novel and efficient means for attaching the rails to the ties in such way that they may be securely held in place, tightened when required and renewed when necessary.

In carrying out my invention I construct each tie in three sections,—a middle section and two end sections. Each of these sections is reinforced by metal rods and the 30 rods of the two end sections are connected with the rods of the middle section by loops which bind the sections together but permit a limited amount of flexibility between the sections to afford sufficient elasticity to take 35 strains from the ties and rails.

I mount the end sections on springs which afford yielding supports for the tie and permit it to sink to a small extent under heavy load and to assume its normal position when the load or weight is withdrawn. The supporting springs are mounted on reinforced concrete blocks fixed in the road bed and the end sections of the tie have a telescopic connection with these blocks 45 so that while the tie can move vertically, sidewise and endwise movement thereof is prevented. The downwardly projecting flanges of the end sections of the tie, which overlap the blocks, are provided with openings permitting access to the springs and other devices below the end sections of the tie and these openings are provided with sliding doors which, when closed, exclude dirt, etc., from the space or chamber between the ends of the tie and the supporting block.

The rails are supported on plates which carry rail fastenings engaging the flanges of the rails and these plates and fastenings are secured to the end sections of the tie 60 by vertical bolts provided with fastening devices, and the connections between the bolts, the plates and the rail fasteners is such that the fasteners may be adjusted laterally with reference to the rails and 65 may be tightened by devices carried by the bolts.

In the accompanying drawings, Figure 1 is a perspective view of a road bed with a portion of a railway track embodying my 70 improvements. Fig. 2 is a section on the line 2—2 of Fig. 4. Fig. 3 shows an elevation of the tie made in accordance with my invention and supporting blocks therefor. It also shows the two rails in section and 75 the fastening devices in elevation. Fig. 4 shows a vertical central section of the parts illustrated in Fig. 3. Fig. 5 is a plan view thereof. Fig. 6 is a view on an enlarged scale and in section showing more in detail the manner of securing the rails to the tie and the manner of connecting one of the end sections of the tie with the middle section thereof. Fig. 7 is a detail view in section on the line 7—7 of Fig. 6. 85

Fig. 1 shows a portion of a road bed and a portion of a railway track constructed in accordance with my invention. The cross-ties are indicated at A, the rails at B, and the road bed at C. Each tie comprises two 90 end sections a , a' , and a middle section a^2 all made of concrete reinforced by metal rods a^3 , a^4 , and a^5 . The end sections are of the same shape, size and construction, while the middle section is of a different shape 95 and is much smaller. The rods a^3 , a^4 , and a^5 are connected by loops b by which means, while the sections are firmly bound together, a limited flexibility is given to the tie as a whole. Any suitable material may be used 100 for rendering the loops non-corrosive and the joints of the sections are covered by metal bands b' which serve to exclude dirt. Those portions of the rods which contain the loops may be constructed of copper, 105 aluminum, or other non-corrosive material, and preferably those portions of the rods near the loops are twisted in the manner indicated in Fig. 6. The end sections of the tie are supported on concrete blocks D reinforced as indicated at d and fixed firmly in 110 the road bed. Springs E are interposed be-

tween the tie sections and the blocks and yieldingly support the tie. Preferably, as shown, the springs are seated in recesses formed in the block and tie sections and 5 wearing plates *e* are interposed between the ends of the springs and the adjacent walls of the blocks and tie sections.

In order to exclude dirt and to hold the ties in position, the end sections of the tie 10 are formed with downwardly extending flanges *f* which overlap the blocks *D* and have a telescopic connection therewith, and in order that access may be had to the spaces containing the springs and other fixtures 15 carried by the tie, the flanges are formed with openings *F* normally closed by sliding doors *G* which are guided vertically in guides or grooves *g* formed in the flanges *f* adjacent the openings *F*. The sliding doors 20 *G* may be held firmly in place by bolts, rivets, or other fastening devices, *g'* so that the doors will rise and fall with the tie, but by withdrawing the fastening device the door may be lifted and access may be had to 25 the springs and other fixtures. If desired, the opening in the end of each section may be large enough to permit of the removal of the block *D* endwise without raising the tie.

The rails *B* rest on plates *H* which in turn 30 rest on the end sections *a*, *a'*, of the tie and these plates support rail fastenings *I* of well known construction. Bolts *J* extend through openings in the plates and through slotted openings *i* in the flanges of the rail 35 fastening and they also extend through the tie sections *a*, *a'* and carry on their lower ends adjusting nuts *j* which are accessible through the openings *F*. Lock nuts are preferably also used and the nuts operate 40 against washers *j'* in the usual way. As will be seen by reference to Fig. 6, the bolts are not embedded in the concrete, but extend through vertical openings formed 45 therein. The upper ends of the bolts have transverse slots which receive wedge-shaped keys *L*, and these keys, when inserted, are held in place by cotter pins *l*. These devices permit the rail fasteners to be adjusted laterally to the proper extent and to 50 be then held firmly in place by proper adjustments given to the nuts *j* and to the wedges *L*. After the rails have thus been connected with the tie any suitable material *m*, such as Babbitt metal, may be poured

into the slots *i* to insure the strength and 55 durability of the fastening. Should the rails at any time "heave" or rise from the ties, shims may be applied in the usual way, and should it be necessary at any time to adjust the fastenings laterally, the material 60 *m* may be cut out and proper adjustments effected.

I claim as my invention:

1. A railway cross-tie, comprising two end sections and a middle section formed 65 of reinforced concrete, the middle section being flexibly connected at each end to the end sections in different vertical planes and said end sections being spring-supported, substantially as described.

2. A railway cross-tie, comprising a middle section and end sections, a plurality of vertically arranged rows of metal rods embedded in the three sections and having interlocking loops which connect the sections 75 with each other between their abutting ends to permit a limited amount of flexibility between the sections.

3. A railway cross-tie, comprising a middle section and end sections made of reinforced concrete and provided with a plurality of vertically arranged rows of flexible connections between their ends, and shields which cover the joints of the sections.

4. A railway cross-tie, comprising a middle section and end sections having downwardly projecting flanges, a plurality of vertically arranged rows of flexible connections between the ends of the sections, reinforced 90 concrete blocks having a telescopic connection with the end sections of the tie and springs interposed between said blocks and the tie.

5. A railway cross-tie, comprising reinforced concrete members having downwardly extending flanges provided with side openings, concrete blocks having a telescopic connection with the tie, springs mounted on the blocks and supporting the tie, and sliding doors mounted on the end sections of the tie.

In testimony whereof, I have hereunto subscribed my name.

GEORGE MARSHALL.
